DESIGN FOR A WRIST CIGARETTE LIGHTER CASING

Norwood Anderson, Chester, N. Y.

Application November 21, 1936, Serial No. 66,083

Term of patent 3½ years

To all whom it may concern:

Be it known that I, Norwood Anderson, a citizen of the United States, residing at Chester, in the county of Orange and State of New York, have invented a new, original, and ornamental Design for a Wrist Cigarette Lighter Casing, of which the following is a specification, reference being had to the accompanying drawing, forming part thereof.

In the drawing:

Figure I is a side elevational view of a wrist cigarette lighter casing in open position showing my new design; and

Fig. II is a front elevational view thereof, the band being fragmentarily shown.

Fig. III is a top plan view thereof.

I claim:

The ornamental design for a wrist cigarette lighter casing as shown and described.

NORWOOD ANDERSON.
